UNITED STATES PATENT OFFICE.

HERMANN BENKERT, OF HARBURG-ON-THE-ELBE, GERMANY.

MEANS FOR ATOMIZING FUEL.

Application filed March 15, 1921. Serial No. 452,601.

To all whom it may concern:

Be it known that I, HERMANN BENKERT, citizen of the German Republic, residing at Harburg-on-the-Elbe, in the State of Prussia, Germany, have invented certain new and useful Improvements in Means for Atomizing Fuel, of which the following is a specification.

This invention relates to a device for atomizing fuel, especially heavy oils for combustion motors and other combustion purposes. The invention consists in directing two individual jets or streams of fuel against each other in axial direction where-
10 by the two jets are forced to dash against each other with great force and the kinetic energy of the jets is thus converted into work which, in its turn, is partly converted into heat so that a part of the fuel is gassi-
15 fied whereas the other part is turned into a very fine mist. The fuel mist resulting from this disintegration and vaporization of the particles is highly combustible and may be exploded in any suitable manner, an in-
20 stantaneous and uniform combustion being assured because of the complete atomization of the fuel.

Numerous attempts to attain the same result have heretofore been made. The fuel has, for instance, been ejected under an extraordianarily high pressure from sharp-edged nozzles, whereby also an atomization was obtained. Further, two fuel nozzles have been arranged oppositely to one an-
30 other, or co-axially, but the jets they pro-
35 duced and directed against each other con-
sisted of a mixture of fuel and air. Also jets of pure fuel have been directed against each other from diametrically opposite
40 points of the cylinder, or of the combustion-
space respectively; but then the total diameter of the cylinder, or of the combustion-
space respectively, lay between the nozzles, and the jets met in the middle of the cylin-
45 der or said space. Furthermore, fuel-noz-
zles have been devised which have an annu-
lar channel followed by a disk-shaped chan-
nel, the fuel being led under high pressure
50 first to the annular channel and being then
made to change its direction, viz, to and
through said disk-shaped channel, the fuel
being thereby directed from the periphery to
the middle. With all these known devices
55 it is, however, impossible to obtain a colli-
sion or concussion of the fuel ejected from
the nozzles as individual jets, thus utilizing

the kinetic energy of the jets for atomizing and gasifying the fuel.

In order to make my invention more clear, I refer to the accompanying drawing, in which similar numerals of reference denote similar parts throughout the several views, and in which:

Figure 1 is a longitudinal section through an atomizing nozzle,

Figure 2 is a longitudinal section through the lower mouth-piece of the atomizing nozzle, and

Figure 3 is a plan of this mouth-piece.

The fuel is supplied to the nozzle-cham-
ber 12 by means of a pipe 8 and in this
chamber a fuel needle 14 is mounted for a
nozzle 16 provided at its lower end with an
atomizing tip 60.

The atomizing tip 60 has but one aperture 75 which terminates at a side of a channel within which the oil-jets, or the small quantities of the oil, dash one upon the other, said aperture being situated just where the jets meet each other. The tip 60 has at its 80 lower end a frusto-conical cavity 61, the ori-
fice 59 of which terminates in a side of the transverse channel 63 connecting the chan-
nels 56 and 57 with each other. The trans-
verse channel 63 is bored into the channel-
body from a side of the latter and the lateral 85 aperture thus formed is closed by a threaded
plug 64. The channels 56 and 57 are bored
downwardly in an oblique direction, into the
body or mouth-piece and thus a hopper-
shaped cavity 62 is formed which comprises
a seat for the fuel-needle 14. The cavity 61
is preferably cone-shaped, forming a hollow
flat cone whose tip, if existing, would lie
about in the middle line of the channel 63
or a little below this line. The edges of the
lateral outlet-opening 59 of the channel 63
are of importance for the oil-mist arising
from the impact of the jets, leaves the chan-
nel through this opening, after which it
spreads within the interior of the cylinder.
The mist will assume the shape of a fan or
of a cone and the direction of the convex
surface of the cone of mist is determined by
straight lines which must be supposed to ex-
tend from the middle of the channel through
the edge of the lateral outlet opening. The
lateral surfaces of the discharge cavity may
be so shaped, or their direction may be such,
that the oil-mist does not touch at all the
sides thereof. This arrangement prevents
the oil-mist from condensing on the walls

of the nozzle-opening whereby the formation of drops in the nozzle is prevented.

Having now described my invention, what I desire to secure by a patent of the United States is:

1. A fuel nozzle for internal combustion engines having a straight transverse channel, a supply channel at each end of the transverse channel and a frusto-conical discharge opening in and intermediate the ends of said straight transverse channel, the vertical axis of said opening being substantially at right angles to said transverse channel.
- 15 2. A fuel nozzle for internal combustion

engines having an inlet opening, two straight channels diverging from said inlet opening, a straight, transverse channel connecting the terminal portions of the diverging channels and a frusto-conical discharge 20 opening communicating with, and having its vertical axis located substantially midway of the transverse channel.

In testimony whereof I have affixed signature in presence of two witnesses.

HERMANN BENKERT.
